UNITED STATES PATENT OFFICE.

ROGER PRESTON, OF NEWTON CENTER, MASSACHUSETTS, ASSIGNOR TO S. S. PIERCE CO., OF BOSTON, MASSACHUSETTS, A CORPORATION OF MASSACHUSETTS.

DESIGN FOR A BOX.

Application filed November 8, 1927. Serial No. 24,044. Term of patent 14 years.

To all whom it may concern:

Be it known that I, ROGER PRESTON, a citizen of the United States, and a resident of Newton Center, county of Middlesex, and State of Massachusetts, have invented a new, original, and ornamental Design for Boxes, of which the following is a specification; reference being had to the accompanying drawings forming a part thereof:

Figure 1 is a perspective view of the box, and

Figure 2 is a plan view of the same.

I claim:

The ornamental design for a box, as shown.

In testimony whereof I affix my signature.

ROGER PRESTON.
